[57] CLAIM

The ornamental design for a flashlight, as shown and described.

DESCRIPTION

FIG. 1 is a perspective view of a flashlight showing my design;

FIG. 2 is a front elevational view thereof, the rear being identical in appearance;

FIG. 3 is a top plan view thereof;

FIG. 4 is a bottom plan view thereof; and

FIG. 5 is a right side elevational view thereof, the left side being a mirror image of that shown.

FIG. 1

FIG. 2

FIG. 3

FIG. 4

FIG. 5
